SHIPPING PACKAGE

Elmer C. Goebert, United States Army,
Philadelphia, Pa.

Application March 26, 1935, Serial No. 13,068

4 Claims. (Cl. 206—3)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a shipping package especially designed for rounds of artillery ammunition but applicable to other articles.

It has been the general practice heretofore to pack complete rounds of ammunition in individual fiber containers and then place a number of such containers in a wooden box. The wooden boxes are expensive, heavy, bulky, and constitute a fire hazard.

With a view to eliminating the wooden boxes, 15 to reducing the bulk and tare weight, and to facilitate handling, stacking and un-packing, it is proposed in this invention to form a shipping package by confining a group of individual containers between a pair of interconnected supporting plates. The supporting plates afford protection to the ends of the containers during transportation, handling, and stacking and provide convenient hand-holds. The plates and containers are inexpensive and need not be salvaged.

25 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a plan view of the improved shipping package.

Fig. 2 is a view in side elevation.

Fig. 3 is a sectional view on the line 3—3 of

40 Fig. 2.

Fig. 4 is a sectional view on the line 4—4 of Fig. 1.

Fig. 5 is an inside plan view of an end plate.

Fig. 6 is a view showing the manner of stacking 45 the packages.

Fig. 7 is an end view of a different formation of the package.

Referring to the drawing by characters of reference, there is shown a shipping package consisting of a plurality of containers A, caps or plates B at the ends of the containers and a connector C for holding the end plates in place.

The containers A are preferably cylindrical though they may be of any shape and they are 50 composed of a light metallic or non-metallic ma-

terial such as fiber. They are provided with a readily removable cover 5 which has a close fit on the body 6. In the present application of the invention the contents of the container consists of a complete round of artillery ammunition 1 5 which is held against movement when the cover is in place.

The plates B are similar and consist of a generally flat supporting surface 8 having a channeled peripheral bead 9 projecting outwardly 10 away from the container. The outer wall 10 of the channeled bead is extended across the plane of the surface 8 to establish a skirt 11 for laterally confining the ends of the containers. The beads 9 are of sufficient extent to afford ample 15 protection for the ends of the container and to provide finger-grip portions whereby the package may be conveniently carried.

The plates B are held tightly against the ends of the containers by means of the connector C 20 which consists of a tie-rod 12 passing through an aperture 13 in each plate B. One end of the rod is provided with a head 14 while the other end is threaded to receive a wing-nut 15. Both the head and the nut are disposed within the 25 depression formed by the bead 9 of each plate. The plates B when thus secured, hold the covers 5 of the containers firmly in place, thereby preventing movement of the round of ammunition in each container and maintaining the closure to 30 protect the contents from deterioration due to moisture.

As clearly shown in Figs. 3 and 4, only the adjacent portions of the ends of a group of containers are supported by the flat surface 8 of the 35 end plates. The outer portion of each container is disposed at the mouth of the channel of the bead. The unsupported outer portions of all of the containers in a group constitute the periphery of each end of the group. The bead 9 may therefore be deformed without transmitting the blow to the ends of the containers. Further protection is also afforded by virtue of the fact that the containers are mutually supporting.

When the packages are piled one on top of another, for example under the conditions of depot storage, the end plates of the bottom tier must take the entire weight and tests have shown that they are capable of supporting the weight without failing or causing damage to the ends of the 50 containers.

The package is formed at the munitions plant and undergoes all types of transportation and rough handling before it reaches the gun. The task of opening the package and removing the 55

rounds of ammunition from the containers may be easily and quickly performed without the aid of tools. The rounds may be repacked with equal facility.

5 I claim:

1. A shipping package comprising spaced similar end plates, each having a channeled peripheral bead with a skirt, means for connecting the plates, and a group of similar individual containers confined by the end plates and within the skirts of said plates, said members having adjacent portions of their ends supported on the plates and outer portions of their ends disposed in the mouth of the channel.

10 2. A shipping package comprising spaced similar end plates, each having a channeled peripheral bead with a skirt, means for connecting the plates, and a group of similar individual containers confined by the end plates, said members

having adjacent portions of their ends supported on the plates and outer portions of their ends disposed in the mouth of the channel.

3. A shipping package comprising a group of similar individual containers, a pair of similar plates each contacting an end of the group of containers, each plate having a peripheral bead projecting on the side of the plate opposite to the containers and means connecting the plates and holding them in clamping engagement with the 10 containers.

4. An end plate for confining a group of members into a shipping package comprising a generally flat supporting member, a peripheral bead on said member and projecting on one side thereof, said bead having a channel, and the outer wall of the channel projecting on the other side of said member and forming a skirt.

ELMER C. GOEBERT.
